UNITED STATES PATENT OFFICE.

MAURICE J. WOHL, OF LONG ISLAND CITY, AND MAX MAYER, OF NEW YORK, N. Y.,
ASSIGNORS TO M. J. WOHL & CO. INC., OF LONG ISLAND CITY, NEW YORK, A COR-
PORATION OF NEW YORK.

REGULATION FOR ARC LAMPS.

Application filed July 25, 1921. Serial No. 487,270.

To all whom it may concern:

Be it known that MAURICE J. WOHL, a citizen of the United States, whose post-office address is Payntar Ave. and Hancock Street, 5 Long Island City, in the county of Queens and State of New York, and MAX MAYER, a citizen of the United States, whose post-office address is 320 Manhattan Ave., New York city, in the county and State of New 10 York, have invented certain new and useful Improvements in Regulation for Arc Lamps, of which the following is a specification.

This invention relates to improvements in the regulation of the light emission of electric arc lamps and particularly to that type of such lamps which are used for photographic illumination and are provided with an automatic carbon-feed mechanism.

In particular this invention constitutes an 20 improvement of the "portable arc lamp" for which an application for Letters Patent has been filed on January 17, 1921, in the U. S. Patent Office under Ser. No. 437,987 by Maurice J. Wohl, one of the inventors of the present improvement.

It is the object of the present invention to provide simple means to vary the light-strength of the lamp instantly without thereby impairing the automatic feeding 30 action.

With these and other objects in view, the invention consists in certain novel combinations of electrical devices and arrangements of parts hereinafter fully described and 35 finally pointed out in the claims.

In the drawings which form a part of these specifications:

Fig. I is a sectional elevation of an arc lamp provided with the improvement, taken 40 on the line I—I of Fig. II.

Fig. II is a plan view of the same lamp. A part of the top plate is broken away to show the mechanism.

Fig. III is a wiring diagram of the lamp 45 embodying the improvement.

Similar characters of reference indicate corresponding parts throughout the various figures.

Fig. I and Fig. II show an arc lamp for 50 which an application for U. S. Letters Patent, Ser. No. 437,987 is pending, this lamp is of the duplex type in which two pairs of carbon electrodes 26—27 are arranged parallel to each other in the same reflector

28. The lower electrodes 27 are suspended 55 by means of the rods 2 and 4 and plate 3 from top plate 1 and the upper electrodes are inserted independently of the mechanism through apertures in plate 1. They are gripped by the clutches 25 which are operated by armature 16 of solenoid 11, rod 17 and lever 20 which has its fulcrum at 21 and is provided with cross bar 23 to lift the clutches simultaneously. Dash pot 14 is suspended 60 from armature 16 and its piston held 65 on the bottom plate 12. The whole mechanism, including the four resistance coils 8, is enclosed by the plates of reflector 38, sides 33, back 35 and top and bottom plates 1 and 36. The two pairs of electrodes are arranged 70 in series and the upper electrodes 26 connected to each other by a short flexible cable 29.

In the improved arrangement shown in 75 Fig. III the connections are as follows:

The terminals 45 and 46 are formed by a reversible plug, consisting of female part 49 and male part 48. The former is provided with four apertures of which 51 is connected to the negative terminal of the line and 53 80 jointly with 55 to the positive terminal. The pins of the male part 48, numbered 50—52—54 are in respective alignment with apertures 51—53—55 that they may enter them; but they are so placed that when either the 85 top or bottom part of the plug is reversed horizontally, pin 50 may enter 55 and 54—51, while in this case 52 will enter the dummy aperture 56.

The solenoid of the improved lamp is 90 provided with two separate windings 11 and 11^A. When the parts 48 and 49 of the plug are connected up as shown, current will flow from the positive line terminal 45 simultaneously through 55—54 and 53—52, both 95 resistance coils 8 and 8^A, both solenoid windings 11 and 11^A to lower left carbon 27^L, forming an arc to 28^L; through cable 29 to 28^R and forming a second arc to 27^R from where it reaches through 50 and 51 the negative terminal 43. If the plug should be reversed, so that pin 50 enters aperture 55 and 54—51 etc. it is evident that resistance 8^A and solenoid winding 11^A are cut out of the 100 circuit and its resistance doubled, while at 105 the same time the polarity of the electrodes is reversed.

This improved arrangement of the elec-

trical connections of the lamp provides an increased number of ampere-turns on the solenoid and an increased magnetization when the lamp operates with the higher amperage. It also provides simple means, remote from the lamp, to alter the light strength instantly without additional mechanism, as a plug of similar type is generally used to connect a portable lamp; the only addition is the third pole on the plug.

Attention is particularly called to the fact that the greater magnetization is provided for the higher amperage. The present invention was developed through experiments to provide means to avoid a certain sluggishness of regulation on the higher amperage. To use the same lamp for different amperages, it was customary to alter the resistance, it is novel however to alter the magnetization. This appears to be desirable for lamps provided with the sensitive mechanism described, to maintain arcs, the length of which is in proper proportion to the current passing through the same. Doubling the current of an arc requires a longer arc to obtain the proper light effect whereby the resistance of the arc is increased, to compensate for the change in current thus produced the additional turns on the solenoid should be added. In a lamp using 12½ amperes and provided with 240 turns about 60 additional turns should be added to provide proper magnetization for the longer arc at 25 amperes when both resistance coils are used in multiple. The invention results in an extremely steady light and sensitive feed under two widely different current strengths.

Having thus described our invention, what we claim as new and desire to secure by Letters Patent is:

1. In an arc lamp a pair of arc forming electrodes, means for forming and regulating an arc of one of two different lengths

and current values between said electrodes consisting of a solenoid having two magnetizing windings, a resistance in series with each winding and switching means to pass current through one of said windings forming means to hold said arc at a relatively short length and low current value or alternatively to pass current through both windings in parallel to hold said arc at a substantially increased length and larger current value.

2. In an arc lamp the combination with line terminals of a pair of electrodes, means for selectively forming and regulating an arc of one of two different lengths and intensities between said electrodes comprising a solenoid having two windings in series with said arc, a pair of resistances each in series with one of the windings of said solenoid, and a switch providing means to connect one winding and resistance singly or both resistances and windings joined in multiple to the same line terminal.

3. In an arc lamp circuit the combination with a pair of arc forming electrodes of magnetic means to separate said electrodes, said magnetic means comprising two magnetizing coils wound on a common core, a resistance in series with each coil; and common means to place alternatively one coil and its resistance or both coils and their resistances in parallel into said circuit.

4. In an arc lamp, the combination with a pair of arc forming electrodes and automatic means for separating said electrodes including a solenoid, of two conductors constituting separate assisting windings on said solenoid, each winding being connected in series with a resistance, these series connections being in parallel with each other and means to connect alternatively one or both series connections in series with the arc.

MAURICE J. WOHL.
MAX MAYER.
